ENGINE STARTING APPARATUS

Paul L. Schneider and Derother H. Dudderar,
Anderson, Ind., assignors to General Motors
Corporation, Detroit, Mich., a corporation of
Delaware

Application October 28, 1948, Serial No. 57,055

4 Claims. (Cl. 290—38)

1

This invention relates to engine starters and its object is to provide for slow initial movement of the starter pinion to facilitate meshing with the engine flywheel gear and to provide for withholding full cranking current from the starting motor until after the motor pinion has been fully meshed with the engine flywheel gear.

Further objects and advantages of the present invention will be apparent from the following description, reference being had to the accompanying drawings, wherein a preferred embodiment of the present invention is clearly shown.

In the drawings:

Fig. 1 is a side view partly in longitudinal section of the starting motor provided with the solenoid for axially moving the starter pinion and for controlling electric circuits.

Fig. 2A is a fragmentary view in the direction of arrow 2A of Fig. 1.

Fig. 2B is a view of part 41 shown in Fig. 1.

Fig. 3 is a left end view of a contact bracket 100 of Fig. 1.

Figs. 4 and 5 are sectional views, respectively, on lines 4—4 and 5—5 of Fig. 3.

Fig. 6 is a view of the contact bracket 100 in the direction of arrow 6 of Fig. 4.

Fig. 7 is a sectional view on line 7—7 of Fig. 1.

Fig. 8 is an enlarged sectional view on line 8—8 of Fig. 7.

Fig. 9 is a wiring diagram.

Referring to Fig. 1, the starting motor 10 has a field frame 11 supporting a frame 12 at its left end and attached at its right end to a housing 13 which is adapted to be attached to the flywheel gear housing which contains the engine flywheel gear 14. Motor armature shaft 15 is supported by bearings in frame 12 and housing 13 and is splinedly connected with a sleeve 16 connected through a one-way clutch 17 with a pinion 18 loosely journaled on the shaft 15 and slidable thereon into mesh with the engine flywheel gear 14 as indicated at 18'.

Sleeve 16 provides collars 20 and 21 providing a groove for receiving rollers 22 provided by the arms of a bifurcated lever 23 pivotally supported by a screw 24 attached to frame 13 and retained by a nut 24a and lock washer 25. Screw 24 is surrounded by a spring 26, one end 26a of which bears against frame 11 and the other end 26b of which is received by a hole in the lever 23. Spring

2

26 normally holds the assembly of sleeve 16, clutch 17 and pinion 18 in the position shown in Fig. 1, the sleeve 16 engaging a shoulder 27 of shaft 15.

5 Lever 23 carries a pin 30 received by a slot 31 in a link 32. Link 32 has a head 33 which is retained in a pocket 34 of a solenoid armature 35 by a ring or washer 36 retained by staking the flange 37 provided by the armature 35. Pin 30 is normally maintained at the left end of slot 31 by a spring 38 the left end of which bears against a washer 39 which bears against the lever 23. The right end of spring 38 bears against washers 39' and 40, the latter retaining a C-washer 41 which is received by the notches 42 of the link 32 as shown in Fig. 2B.

10 Armature 35 is supported for axial movement by a non-magnetizable tube 51 provided by the solenoid assembly 50 which comprises magnetizable shell members 52, 53, discs, 54, 55, a core 56 and discs 57, 58. Tube 51 is supported by core 56 and by flange 59 of disc 58 and is surrounded by a magnet coil 60. Flange 59 supports a metal ring 61 which retains a felt ring 62 engaging the armature 35.

15 The armature 35 is connected with a rod 70 which supports a ferrule 71 between the flanges of which there are located three insulating discs 72, 73, 74 which insulatingly support the contacts 75.

20 Rod 70 provides a groove 76 which receives a C-washer 77 retained by a spring 78 which forces a washer 79 against the right end of ferrule 71 and pushes the left end of said ferrule against a snap ring 80 received by a groove at the 25 left end of rod 70.

25 To the disc 54 there is attached a plate 81 providing ears 82 for supporting a pin 83 which provides a pivot for a lever 84 made of non-conducting material. As shown in Fig. 8, lever 84

30 supports a contact 85 retained thereon by a stud 86 riveted to the contact and passing loosely through a hole 87 in the lever and surrounded by a resilient metal disc 88 which urges the contact 85 upwardly until the shoulder 89 provided by the 35 head of the rivet engages the underside of lever 84. Contact 85 is engageable with contacts 90 and 91 (Fig. 6).

35 Contact 90 is provided by a bracket 92 attached to a bracket 100 by a terminal screw 94 and insulated therefrom by non-conducting plate 93. A

projection 96 on bracket 92 extends into a hole in non-conducting plate 93 to prevent bracket 92 from turning about terminal screw 94. Contact 91 is provided by bracket 95 confined between the plate 93 and a contact 97 provided by a terminal screw 99 supported by a bracket 100 and insulated therefrom as shown in Fig. 4. Fig. 5 shows another terminal screw 101 insulatingly supported by the bracket 100 and providing a contact 102. Bracket 100 insulatingly supports a terminal screw 104.

Referring to Fig. 9, a resistance 110 is connected with terminal screws 94 and 101 which is connected with a starting motor 120. Terminal 99 is connected by a wire 111 with battery 112. A manually controlled switch 113 connects wires 111 with terminal screw 104 to which the non-grounded end of coil 60 is connected.

Normally the spring 26 locates the lever 23 and hence the armature 35 and the contacts 75 in the position shown in Fig. 1. Disc 74 by engaging lever 84 holds it into the position shown against the action of a spring 84s thereby maintaining contact 85 out of engagement with contacts 90 and 91.

To start the engine, the switch 113 is closed thereby connecting coil 60 with the battery and thereby attracting armature 35 toward the core 56. Initially, armature 35 moves to allow spring 84s to move contact 85 into engagement with contacts 90 and 91 (Fig. 9) so that current passes to motor 120 through resistance 110, having a value such that the motor develops torque sufficient to rotate the pinion 18 while out of contact with gear 14 but not sufficient to rotate the pinion in case its teeth abut gear 14 without meshing. Initial movement of armature 35 also compresses spring 38 as link 32 moves until the right end of slot 31 engages pin 30, causing lever 23 to rotate on pin 24, moving pins 22 and collar flange 21. Therefore after the motor 120 receives current through resistance 110 and before pinion 18 engages gear 14, the pinion is turning slowly with the object of arriving at a meshing position by the time it engages the gear 14. If there is an abutment of gear teeth, motion of the armature 35 is arrested and switch 113 is opened to disconnect the coil 60 and to allow the spring 26 to return the lever 23 and pinion 18 to normal position. The switch 113 is closed again to obtain a slow rotation of the pinion 18 and a different angular position thereof by the time it engages the gear the second time. If the pinion is not in meshing position following the first closing of switch 113, it usually is in meshing position following the second closing of the switch.

Following the positioning of pinion 18 for meshing with the gear 14, the armature 35 continues its movement to cause contact 75 to engage contacts 97 and 102, thereby shorting the resistance 110 and causing cranking current to pass to the motor 120. Armature 35 still continues to move until it abuts core 56, causing washer 77 to compress spring 78, since washer 79, 74 and contact disc 75 are no longer free to move. When armature 35 abuts core 56, pinion 18 has moved into its fully meshed position with the ring gear 14. The motor cranks the engine and when the engine becomes self-operative, the pinion 18 overruns the sleeve 16 by virtue of the overrunning clutch 17. When the engine has been started, the switch 113 is open, the solenoid is deener-

gized and the spring 26 restores the parts to normal position as shown in Fig. 1.

If the engine should fail to start after the pinion has been fully meshed with the engine gear, the switch 113 is opened to deenergize the solenoid coil 60 whereupon spring 38 will expand to move the link 32 toward the right until the left end of slot 31 engages pin 30. This movement is sufficient to separate contact 75 from contacts 97 and 102 leaving the battery connected with the motor through the resistance 110 which is high enough in value to prevent overheating of the motor and wiring connecting it with the battery; and, furthermore, the torque, which the motor develops under those conditions, is so low that the spring 26 can retract the pinion from the engine gear and return the armature to normal position and separate contact 75 from contacts 90 and 91.

20 While the embodiment of the present invention as herein disclosed, constitutes a preferred form, it is to be understood that other forms might be adopted.

What is claimed is as follows:

25 1. Engine starting apparatus comprising a battery, a motor, a pinion movable into mesh with an engine gear, a one-way clutch connecting the motor with the pinion, a solenoid having an armature and a magnet coil, a solenoid controlled switch having a terminal connected with the battery, a terminal connected with the motor and a contact carried by said armature for connecting the terminals, a resistance having one end connected with one of said terminals, a second solenoid controlled switch for connecting the other end of said resistance with the other of said terminals, means operable by the armature to move the pinion into engagement with the engine gear, means for demeshing the pinion and returning the armature to normal position after the engine is started, means operable when the solenoid is energized for effecting closing of the second switch before engagement of the pinion with the gear and for closing the first switch after engagement of the pinion with said gear, said last named means being so constructed that the second switch is closed as long as the solenoid is energized and the resistance is short circuited when the first switch is closed, and a manually controlled switch for connecting the battery with the coil.

2. Apparatus according to claim 1 in which the means which transmits motion from the armature to the pinion includes a spring which is stressed during movement of the armature between a position effecting substantially complete meshing of the pinion and a position effecting closure of the first solenoid controlled switch whereby, in case the engine fails to start and the pinion demeshing spring is unable to function due to the force applied by the motor to the pinion, the opening of the manually controlled switch results in deenergization of the solenoid, in release of the motion transmitting spring to open the first solenoid controlled switch, in such reduction of force applied to the pinion that the pinion demeshing spring is effective, and in return of the armature to normal position to effect opening of the second solenoid controlled switch.

3. Apparatus according to claim 1 in which the second solenoid controlled switch has a movable contact supported by a lever urged by a spring into switch closing position and which an abutment moves with the armature to engage the lever to open the switch when the armature

is moved to normal position by the pinion de-meshing spring.

4. Apparatus according to claim 1 in which the means for transmitting motion from the armature to the pinion includes a lost motion connection and in which the closure of the second switch is effected substantially when the lost motion is taken up so that the slow rotation of the pinion begins substantially at the time it begins its movement toward the engine gear.
